UNITED STATES PATENT OFFICE

RASMUS K. MILLER, JR., OF WINCHESTER, MASSACHUSETTS

MATTRESS TICK

Application filed December 26, 1929. Serial No. 416,406.

This invention relates to the tick constituting the visible element of a mattress, and enclosing a yielding mattress element which may be a resilient structure including metallic springs, or a filling of fibrous material.

The invention is embodied in a tick having reinforcing means increasing its desirability in certain respects, as hereinafter explained.

Of the accompanying drawings forming 10 a part of this specification,—

Figure 1 shows in perspective a tick embodying the invention, adapted to enclose a mattress element which includes springs, the tick being partly open for the reception of 15 said element.

Figure 2 is a fragmentary section on line 2—2 of Figure 1.

Figures 3 and 4 are fragmentary perspective views, showing opposite sides of the 20 border of the tick.

Figure 5 is a fragmentary perspective view, showing a corner portion of a tick embodying the invention and constituting an element of a mattress which includes a fibrous 25 filling.

Figure 6 is a fragmentary section on line 6—6 of Figure 5.

Figures 7 and 8 are enlargements of portions of Figure 6.

Figure 9 is a fragmentary section on line 9—9 of Figure 5.

The same reference characters indicate the same parts in all of the figures.

In the drawings, 12 designates the bottom and top sides, and 14 the sections of the margin of a mattress tick. One of the sections 14 is shown displaced in Figure 1, to permit the insertion of a yielding mattress element in the tick, said section being subsequently closed.

A tick embodying my invention comprises spaced apart vertical reinforcing cords 15 laid on one side of the border and attached thereto by stitches, the cords extending from 45 the lower to the upper edge of the border.

In this instance, the attaching stitches, which may be formed by a sewing-machine of the cord-attaching type, includes portions 16 (Figure 3), bearing on the side of the border 50 opposite the side on which the cords are laid,

and extending parallel with the cords, and portions 17 (Figure 4) bearing on and extending across the cords.

When the tick encloses a spring structure which does not have an extended bearing 55 on the border, the vertical cords 15 reinforce the inherently limp border and prevent the same from wrinkling and imparting an untidy appearance to the mattress, the cords being sufficiently stiff to prevent the 60 wrinkling of the border, without being so rigid as to prevent a person from sitting comfortably on an edge portion of the mattress. In other words, the cords are resiliently flexible and adapted to be flexed by the weight 65 of a sitting person, and straighten to impart smoothness to the border when the weight is removed.

The tension of the attaching stitches is such that the cords are caused to indent the 70 side of the border on which they are laid, and bulge the opposite side and form ribs thereon. The cords project from the border sides on which they bear, so that ribs are formed on each side of the border. The cords may bear 75 on either the inner or the outer side of the border. In either case, the outer side of the border is provided with projecting spaced apart ribs which diversify it and impart an ornamental appearance to the mattress.

In the stuffed mattress shown in part by Figures 5 and 6, said mattress including a fibrous filling 18, the border is characterized as above described, and the sides 12 are characterized by horizontal reinforcing cords 19, attached thereto by stitches and spaced from 85 and extending substantially parallel with the margins of the sides.

The cords 15 and 19 in this embodiment of 90 the invention are adapted to bear on the inner surfaces of the mattress portions 14 and 12, and arranged to support the ligatures often employed in stuffed mattresses to impart the beaded or roll effect indicated by Figures 5 and 6.

Said ligatures are provided by stout threads 20, inserted in zigzag formation in corner portions of the mattress in a manner well known by upholsterers, each thread having bends 20a and 20b exposed on the exter- 100

nal surface of the mattress. The bends 20a extend across and are laid on the ribs formed by the reinforcing cords 15 on the border, and the bends 20b extend across and are laid 5 on the ribs formed by the reinforcing cords 19 on the sides. In each case, the exposed portions of the ligatures are prevented by the reinforcing cords from being pulled through and rupturing the tick material. In other 10 words, the reinforcing cords anchor said exposed portions on the external surfaces of the mattress.

The last described embodiment of the invention is not limited to a mattress having 15 the particular formation shown by Figures 5 and 6.

It will be seen that the resiliently flexible border-reinforcing cords 15 may reinforce the border either by stiffening it to maintain 20 its sides in a smooth condition and permit it to be flexed by the weight of a person, as described, or by preventing the ligature portions 20a from cutting or tearing through the border.

25 It will also be seen that a tick reinforced as to its border by the cords 15, and as to its sides by the cords 19, is a desirable element of a stuffed mattress to which a predetermined form is imparted by the ligatures 30 20, said cords preventing liability of the cutting or tearing of the sides and border by the ligatures, and therefore preventing departure from the predetermined form of the mattress.

35 I claim:

A mattress tick comprising opposite sides, an intermediate border, spaced apart vertical reinforcing cords bearing on the inner surfaces of the border, stitched thereto, and extending 40 from the lower to the upper edge thereof, and horizontal reinforcing cords bearing on the inner surfaces of the sides, stitched thereto, and extending substantially parallel with the margins thereof, 45 said reinforcing cords being adapted and arranged to support zigzag ligatures connecting the margin and the sides of the tick and extending through portions of a fibrous filling, the bearing of the reinforcing cords on the inner surfaces of the tick sides and border preventing the ligatures 50 from being pulled through the portions of said sides and border with which they are engaged.

55 In testimony whereof I have affixed my signature.

RASMUS K. MILLER, JR.
